US0D1059339S

(12) **United States Design Patent** (10) **Patent No.:** **US D1,059,339 S**
(45) **Date of Patent:** **** Jan. 28, 2025**

(54) **PEDESTAL**

(71) Applicant: **Sensormatic Electronics, LLC**, Boca Raton, FL (US)

(72) Inventors: **Channing Miller**, Fort Lauderdale, FL (US); **Sergio M. Perez**, Lake Worth, FL (US)

(73) Assignee: **Sensormatic Electronics, LLC**, Boca Raton, FL (US)

(**) Term: **15 Years**

(21) Appl. No.: **29/884,418**

(22) Filed: **Feb. 10, 2023**

Related U.S. Application Data

(63) Continuation of application No. 29/748,215, filed on Aug. 27, 2020, now Pat. No. Des. 981,381.

(51) **LOC (15) Cl.** **14-03**
